(57) **CLAIM**

The ornamental design for an receptacle adapter, as shown and described.

DESCRIPTION

FIG. 1 is a perspective view of a female receptacle adapter embodying our design;

FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof as seen along lines 6—6 of FIG. 4;
FIG. 7 is a bottom plan view as seen along lines 7—7 of FIG. 5;
FIG. 8 is a perspective view of a male receptacle adapter embodying our design;
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top plan view thereof as seen along lines 13—13 of FIG. 12;
FIG. 14 is a bottom plan view as seen along lines 14—14 of FIG. 11;
FIG. 15 is a perspective view of another female receptacle adapter embodying our design;
FIG. 16 is a front elevational view thereof;
FIG. 17 is a rear elevational view thereof;
FIG. 18 is a right side elevational view thereof;
FIG. 19 is a left side elevational view thereof;
FIG. 20 is a top plan view thereof as seen along lines 20—20 of FIG. 19;
FIG. 21 is a bottom plan view as seen along lines 21—21 of FIG. 18;
FIG. 22 is a perspective view of another male receptacle adapter embodying our design;
FIG. 23 is a front elevational view thereof;
FIG. 24 is a rear elevational view thereof;
FIG. 25 is a left side elevational view thereof;
FIG. 26 is a right side elevational view thereof;
FIG. 27 is a top plan view thereof as seen along lines 27—27 of FIG. 25; and,
FIG. 28 is a bottom plan view as seen along lines 28—28 of FIG. 26.
The broken lines are for illustrative purposes only and form no part of the claimed design.
